United States Patent

Des. 239,585
Patented Apr. 20, 1976

239,585

STUDY CARREL OR SIMILAR ARTICLE

John A. Mahan, Kanata, Ontario, and John F. Tyson
and Robert E. Hillmer, Ottawa, Ontario, Canada, as-
signors to Northern Electric Company Limited,
Montreal, Quebec, Canada

Filed Sept. 23, 1974, Ser. No. 508,094

Term of patent 14 years

Int. Cl. D6—03

U.S. Cl. D6—181

Fig. 1

Fig. 2

Fig. 3

FIG. 1 is a front perspective view of a study carrel showing our design;

FIG. 2 is a view in front elevation; and

FIG. 3 is a plan view thereof.

The side of the modesty panel not shown in FIG. 2 is plain and unornamented.

We claim:

The ornamental design for a study carrel or similar article, substantially as shown and described.
